UNITED STATES PATENT OFFICE.

JOHN T. HOPE, OF KANSAS CITY, MISSOURI.

PNEUMATIC DUST-COLLECTOR AND SWEEPER.

SPECIFICATION forming part of Letters Patent No. 705,585, dated July 29, 1902.

Application filed July 20, 1901. Serial No. 69,001. (No model.)

To all whom it may concern:

Be it known that I, JOHN T. HOPE, a citizen of the United States of America, residing at Kansas City, in the county of Jackson and 5 State of Missouri, have invented certain new and useful Improvements in Pneumatic Dust-Collectors and Sweepers; and I do hereby declare that the following is a full, clear, and exact description of the invention, such as will 10 enable others to make and use the same, reference being had to the accompanying drawings, forming a part of this specification.

The object of my invention, primarily, is to remove the dust and debris from any surface 15 upon which the dust is deposited during the passage of a receiver over the deposited dust into the receivers in which the dust is drawn by suction; secondly, to collect the dust and debris in either a forward or reverse direction 20 of the movement of the dust-receiver; third, to collect the dust-receptacles from a moving vehicle and avoid obstruction; fourth, to conduct the dust and debris from the separate dust-receivers to a centrally-located suction 25 and blast apparatus upon a vehicle, and, fifth, to convey the collected dust from the suction and blast apparatus upon the vehicle to suitable closed receptacles in advance or in rear of the vehicle.

30 The invention consists in the novel construction and combination of parts, such as will be first fully described, and specifically pointed out in the claims.

In the drawings, Figure 1 is a plan view of 35 separate motor-propelled vehicles or cars for a street-railway, upon one of which is located a suction and blast apparatus and the novel dust-collecting devices and upon the other vehicle or car the receptacle or compartment 40 for the collected dust. Fig. 2 is a side view of the cars and of the invention as seen in Fig. 1, showing the trolley for conducting the current of electricity from an overhead wire to the motors on the car. Fig. 3 is a view, 45 upon a smaller scale than in Fig. 1, of the car or vehicle carrying its suction and blast apparatus and the lateral dust-receivers, taken from the end of the car upon the line $x-x$ of Fig. 1. Fig. 4 is a detail side view, enlarged, 50 of one of the novel dust collectors and receivers, showing one of the controlling-rods for raising the dust-collector and sweeper in an

elevated position. Fig. 5 is a vertical sectional view of the dust-collecting receiver and sweeper, showing the devices for raising 55 and lowering the dust-sweepers. Fig. 6 is a detail broken view of the inner end of the receiver. Fig. 7 is a detail side view of the flexible joints on the elbow connecting the horizontal tube beneath the car with the receivers. Fig. 8 is a vertical sectional view of the connecting flexible joints as seen in Fig. 7. Fig. 9 is a detail broken view of the hinged joint of the crank-rods operating the receivers upon the platform of the car. Fig. 10 is 65 a transverse sectional view of a portion of the platform of the car, taken upon the line $y-y$ of Fig. 1 and showing the horizontal air-suction tube and the auxiliary stationary dust-receiver between the track-rails connected 70 with the said tube. Fig. 11 is a sectional view of the portion of the platform of the car and the suction-tube and receivers, taken at right angles to and upon the line $2-2$ of Fig. 10. Fig. 12 is a vertical sectional view of the air-suction and blast-fan case, showing the induction-pipe leading to the horizontal tube 75 beneath the platform of the car. Fig. 13 is a plan view of the retaining device for the crank-rod on the platform of the car. 80

Similar letters of reference indicate corresponding parts in all the figures of the drawings.

Referring to the drawings, A represents an ordinary platform-car, the platform of which 85 is mounted upon the forward and rear trucks a^2 and a^3 , the flanged wheels a^4 of which trucks are seen bearing upon the track-rails B. For the purpose of illustration I have designed to employ the usual track-rails of 90 the street-railway cars, over which the platform-car A is propelled to clean the street and utilize the same motive power employed by the street-cars. When this power is not available, the platform-car may be otherwise 95 propelled.

Upon the platform a of the car, near its forward end and at a point equidistant from the sides of said platform, is an air suction and blast apparatus C. Said apparatus consists 100 of a case c, in which is a rotary suction and blast fan of ordinary and well-known construction and not necessary to illustrate. The fan-operating shaft c', as seen on Fig. 3,

is journaled at one end in the standards D D, the other end of which shaft extends within one side of the fan-case and supports the rotary suction and blast fan C. With the other 5 side of the case c and the induction-opening c² in said side is rigidly connected a vertical conducting-spout E, which is bent at its upper end to form an elbow and connected with the opening c³ in case c. The lower end of the spout 10 E extends through the platform a of the car and to a position a short distance below the under side of said platform, and which lower end is connected with the upper side of a horizontal tube F, extending an equal distance 15 to the width and in a transverse direction to the platform a of the car. Upon each end of the tube F, which is of the proper size to admit of the free passage of dust, are socket-joints f f, which receive the socket-joint h' on the elbow H, hereinafter described.

G represents the novel pneumatic dust-receivers, which are arranged in position upon each side of the car and near the ground, 25 and each extends in length from a point beneath the elbow-joints f f outwardly and nearly the width of the street between the track-rails and the usual curbing and as near the gutter as the curvature of the gutters will 30 permit. Each receiver G consists of a longitudinal tube or trunk which is elliptical in shape in cross-section, the oppositely and outwardly curved sides g g of which extend from the line g⁴ of the top downwardly toward the ground and are spread apart, leaving a longitudinal opening g' extending the 35 length of the under side of the receiver, upon the lower ends of which sides are downwardly-extended flanges g² g². The inner end of the receiver G beneath the platform of the car extends in height a considerable distance, so as to give free passage for the volume of dust, and from said inner end to the outer end the height of the receiver G 40 gradually decreases, the line g⁵ of the top of said receiver describing a downwardly-inclined plane. The rear end of the receiver G extends downwardly from the top of the receiver and inclines outwardly at an angle 45 to said top and is closed by the end plate g³, conforming to the curved ends of the receivers. In the top of receiver G and on the end beneath the platform a of the car is an opening g⁴. Upon the top of the receiver and extending around the opening g⁴ is a circular 55 upwardly-extended neck g⁵, the sides of which extend downwardly in curved lines on opposite sides g g of the receiver G and are riveted thereto. At the upper end of the 60 neck g⁵ is an outwardly-extended flange g⁶.

H represents the flexible curved-joint elbow-pipe connecting the receivers with the horizontal suction-tube F, upon the lower end of which is an outwardly and downwardly extended annular flange h, which extends loosely around the flange g⁶. Extending around the neck g⁵ is a ring g⁷, which is secured by bolts

g⁸ to the lower end of the annular flange h, thus permitting the neck g⁵ to turn freely in the flange h. Upon the upper end of the elbow H is a joint h', which is slightly smaller and fits within the socketed end of the tube F. Through the sides of the socketed ends f and h' of the elbow and tube extends a transverse pivot-bolt f². 75

Upon the outer side of each flange g² g² of the receiver G are a series of eyes or loops g⁹, and extending in the longitudinal direction of the receivers in said loops are the crank-rods I, upon which rods near the inner ends of the receivers are cranks i i. With said rods upon each side of the receiver are connected rigidly a series of downwardly-extended arms i², which extend a short distance from the rods I, and upon the outer surfaces 80 of which arms is a longitudinal plate i³, the upper edge of which is near the rods I and the lower edge of which is connected with the ends of the arms i². Upon the outer surface of the plate i³ are brushes L, which are arranged at short distances apart in the longitudinal direction of plate i³ and which consist, preferably, of bamboo fiber, the lower ends of which fibers extend to the surface of the ground. Upon the outer and inner sides 85 of the brushes L are longitudinal plates i⁵ of the same width of the plates i³. Upon and covering the outer surface of the inner plate i⁵ is a longitudinal strip of rubber or canvas cloth or apron i⁶, extending the length of the receiver G, the lower edge of which cloth or apron extends downwardly to within a short distance of the lower ends of the fibers of the series of brushes L and which serves to prevent the suction of air from the receivers to pass throughout the brushes. Upon the outer side of the apron i⁶ is a longitudinal plate i⁷ of the same length and width as the plate i³. Through the arms i² and the clamping-plates i⁸ i⁹ and also the rubber cloth i⁶ extend the 90 clamping-bolts i⁷, upon each of which is a head i⁸ and a nut i⁹, and which bolts are arranged at short distances apart in the longitudinal direction of the plates i³ i⁵. 95

With the cranks i i on the rods I I are pivotally connected the lower ends of the sweeper-operating rods M M, which extend upwardly a short distance in a direct line and thence bent at an angle at n^X and extended through suitable openings in the platform a of the car and are provided with rings or handles m m. Upon the sides of the rods M M at the point where they pass through the openings in the platform of the car are teeth m', which serve to engage with the sides of said openings and hold the rods when the cranks i i are operated alternately to lift the sweeper L. 110

With the outer ends of the receiver G and with the top portion g⁴ is secured one end of an outwardly-extended pivot-bolt n', which connects pivotally the outer ends of the forked arms n² n³ of the caster or swivel wheel N with the plate n. 115

Upon the top of receiver G, a short distance

from the pivot-plate n , in the direction of the rear end of the receiver and connected with the sides g is an eyebolt o . Through the eyebolt o extends one end of the operating-rod O , the extreme end of which is bent upwardly at o' to secure the rod from removal. The other end of rod O extends in the direction of the upper end of the elbow H and near the upper side of said elbow and is pivotally connected at o^2 to the lower forked end o^3 of a vertical crank-rod o^4 , the upper end of which rod extends upwardly through a suitable opening in the platform a a short distance inwardly from the side of the platform and also a short distance upwardly above the upper side of the platform through a cap o^5 on the inwardly-extended braces o^6 o^6 , and upon said rod is a crank o' , by means of which the receiver is vibrated laterally or held from movement while the street is being cleaned of dust.

Upon the shaft c of the suction and blast apparatus is a band-wheel c^3 , over which extends one end of a belt c^4 , the other end of which is extended over the band-wheel c^5 on an electric motor P , arranged in position in the rear end of the platform a in line with the suction and blast apparatus C , the two ends of the belt being united in the ordinary manner.

On the platform a of the car, immediately in rear of the suction and blast apparatus C , is a stationary upright hollow post R , upon which is the trolley-arm r , carrying the trolley r' , which moves over the overhead wire r^2 , through which the current passes from the main electric plant of the street-railway motive power. The conducting or branch wires r^3 connect with the trolley r' , pass downwardly within the hollow post R , thence to the respective binding-posts on the motor P . Beneath the platform of the car is the car-actuating motor S , which receives the current from the branch wires r^3 r^3 and the motor P through the branch wires r^3 r^3 r^4 r^4 , which extend through the platform of the car, the shaft of motor S being geared to the axle of the rear truck a^3 in the ordinary manner.

With the induction portion c^6 of the fan-case C is connected one end of the dust-distributing pipe T , which extends upwardly a short distance and then branches at t in opposite directions, the pipes t^2 t^2 extending forwardly and rearwardly to vertical lines extending through the ends of the platform a .

U represents a platform-car the wheels of which are mounted on track-rails B and which car is coupled with the platform-car A . Upon the platform u of the car U is a tank u' , having an opening u^3 in the top. The tank u' extends the length of platform u , and its sides extend in height a short distance above the height of the branch pipes t^2 t^2 . In the forward end of the tank u' and near one side of the tank is a short length of pipe u^4 , upon which is a flange u^5 . Upon the ends of the branch pipes t^2 t^2 are coupling-flanges u^7

u^7 . One of the branch pipes t^2 , having the coupling-flange u^7 , is coupled with the flange u^5 on the pipe u^4 , connected with the end of the tank u' . In each pipe t^2 t^2 is a damper t^1 . In order to take up the dust between the track-rails, I employ a separate receiver and dust-collector V , which is arranged beneath the platform a of the car and in rear of the horizontal dust-tube F , the construction of which is similar to the receiver G , the connection with the top of the receiver being an elbow v , which extends forward and is connected rigidly with the rear side of tube F . From the elbow v the top of the receiver decreases in height in opposite directions toward their outer ends, the sweepers v' extending from the lower edge of the receivers to the ground, as described of the brushes and apron L , and which are raised and lowered alternately by the operating-rods v^2 v^2 , as seen on Fig. 11, which extend upwardly through suitable openings in the bottom of the car and are provided with handles v^3 v^3 .

In operation the receivers G G are moved by the crank o^7 , which operates the rods o^4 from the side of the car to a lateral position to the car, as seen in Fig. 1, the outer end of the receiver G extending nearly the width of the street from the track-rails B toward the line of the street-curbing on opposite sides of the street. The rods M M are operated upon the sides of the receivers G G in the direction of the forward movement to lower the brushes L and the apron i^6 . The lower ends of the fibers of the brushes and the lower edge of the apron i^6 come into contact with the pavement or street-surface, and the rods M M on the other or rear side of the receivers G G are operated toward the brushes and apron out of contact with the surface of the street, in which position the teeth m' engage with the sides of the opening in the platform a of the car and hold the rod from movement. During the forward movement of the receivers G G the brushes are permitted to move rearwardly sufficiently to take up adhered substances and carry forward, sweep, and collect the dust, the apron serving to prevent the air from passing through the brushes. The power from the overhead wire is transmitted to the motors P and S and the car propelled on the track B along the center line of the street. This power is transmitted through the belt c^4 to the air suction and blast apparatus C , the suction power of which is extended through the tubes E and F , the elbow H , and the receivers G G , the suction extending the length of the receivers and to the surface of the street over which they are moved and to the dust collected by the brushes, and as the dust is collected by said brushes and apron the motion of the blast-fan causes a vacuum in the receivers G G and draws the dust into the receivers, thence up the elbow H to the suction and blast apparatus through tubes F and E and is forced out of the apparatus by the blast into

the branch pipe t^2 , then to the tank u' and the side of said tank in rotary currents, the air finding a vent through the opening u^3 in the top of the tank after depositing the dust in the tank. In the operation of the blast apparatus C the dust is also collected by the receiver V beneath the car A and expelled through the branch eduction-pipe t^2 into tank u' , the brushes and apron on the forward side of the receiver V being adjusted by the rods v^2 in the manner described by the rods M M on receiver G G. Any vertical movement which may occur in passing over an uneven pavement is provided for in the elbow H, the socket-joint h' and f , with the tube F, permitting a free movement of the elbow the proper degree, and also by means of the hinged connection of the rod O with the crank-rod o^4 . The vertical movement is independent of the rotary movement of the crank-rod. In meeting obstructions upon the street the crank o^4 is operated to vibrate the outer end of the receivers toward the side and rear of the car, this movement being permitted by the flexible joints g^6 and h , which connect the elbow H with the receivers and which permits of the rotary movement of the flange g^6 in the enlarged flange h on the end of said elbow. In a reverse movement of the car A one of the branch pipes t^2 of the dust-distributing pipe T is disconnected from the tank u' and the other branch pipe t^2 connected with the tank and the brush and apron lowered in position upon the opposite side of the receivers G G and V in the movement caused by said reversal of movement and raised in position upon the sides of the receivers on which they were previously operated to collect the dust. The damper t^5 in the branch pipe t^2 is opened and closed according to the direction and movement of the car.

In my invention the usual sprinkling of the street to merely allay the dust is avoided, and no dust or deposits of animal refuse remains, the entire quantity of dust and debris in the path of the receivers being collected and discharged into the tank u' , from which the collected dust is removed through a door u^6 , hinged at u^7 to the side of the tank u' . In the rearward movement of the receivers G G the swivel-wheels N N turn upon the pivots n' and follow the line of direction of the outer end of the receivers as they move toward the sides of the car.

The crank-rods a^4 , operating the receivers G G, are held in position, and also the receivers, by a notched wheel o^{12} on the crank-rod, which is near the upper surface of the platform a of the car, as seen in Fig. 13, the ratchet o^9 consisting of a T-shaped pivoted arm, which engages with the square notches in the wheel and prevents its rotation and that of rod o^4 . Other devices may be employed in place of the wheel and ratchet, if preferred.

When the usual power required to operate the suction and blast apparatus and the car

is not available, I intend to employ an engine such as a gasoline-engine and the usual traction of the desired power upon the wheels, power, and any vehicle suitable for the support of the suction and blast apparatus.

It is obvious that modifications may be employed in the invention and which will readily occur in the various details of construction and which are within the scope of the invention, and by the employment of these modifications the invention may be applied to buildings for sweeping a floor and the receivers employed in the various rooms of the building and the dust drawn to the suction and blast apparatus properly located in the building or elsewhere, as may be found desirable.

Having fully described my invention, what I now claim as new, and desire to secure by Letters Patent, is—

1. A pneumatic dust-collector comprising a vehicle, a motor, a suction and blast apparatus upon said vehicle, actuated by said motor, a transversely-extended air - suction and vacuum-forming dust-receiver having a longitudinal opening upon its under side for the entrance of the dust and movable upon the surface of the ground, conductors for the dust connected with said receiver and also connected with the induction - opening to the said suction and blast apparatus having swivel-joints, and aprons hinged to the said receivers, means for vibrating the receiver laterally in position on the side of the vehicle and elevating devices connected with said hinged aprons and adapted to raise and lower said aprons alternately.

2. A pneumatic dust-collector and sweeper, comprising a vehicle, a motor, a suction and blast apparatus upon said vehicle actuated by said motor, a transversely-extended air-suction and vacuum-forming dust-receiver having a longitudinal opening upon the under side for the entrance of dust, movable upon the surface of the ground, conductors for the dust connected with said receivers and also connected with the induction-opening to the suction and blast apparatus, having swivel-joint combined dust - brushes and aprons hinged at said receivers, means for vibrating said receivers laterally in position to the side of the vehicle, and elevating devices connected with the hinged brushes and apron.

3. A pneumatic dust-collector and sweeper for streets comprising a vehicle, a motor, a suction and blast apparatus upon said vehicle actuated by said motor, a transversely-extended air - suction and vacuum-forming dust-collecting receiver upon the side of said vehicle and the surface of the street, having longitudinal openings upon its under side, a conductor for the dust connected with said receiver and also connected with the induction-opening to the suction and blast apparatus, combined brushes and aprons upon opposite sides of said receivers, hinged there-

to, and means for raising and lowering the combined brushes and aprons upon opposite sides of the receiver alternately.

4. A pneumatic dust-collector comprising a vehicle, a motor, a suction and blast apparatus upon said vehicle actuated by said motor having induction and eduction openings and an air-suction and vacuum-forming receiver movable upon the surface of the street and conductors for the dust connected with said receiver and also connected with the induction-opening to the suction and blast apparatus, a receptacle for the dust having an opening in its top and oppositely-extended dust-conducting pipes connected with the

eduction-opening to the suction and blast apparatus one of which pipes is connected with one side and end of the dust-receptacle and suitable valves in said pipes.

20 5. A dust-collector consisting of a longitudinally-extended receiver, having an opening upon its under side for the reception of the dust, traveling supports for said receiver, flexible conductor connected with said receiver, an air-suction apparatus connected with said conductor, a hinged support upon said receiver and dust-collecting fibers upon said support, and an apron, substantially as described.

30 6. A dust-collector consisting of a longitudinally-extended receiver, having an opening upon its under side for the reception of the dust, traveling supports for said receiver, flexible conductor connected with said receiver, a receptacle for the collected dust, an air-suction apparatus connected with said conductor and a conductor leading from said apparatus to said dust-receptacle, a hinged support upon said receiver and dust-collecting fibers upon said support, and an apron, and means for raising and lowering said fibers and apron.

7. In a pneumatic dust-collector and sweeper, a vehicle, a motor, a suction and blast apparatus upon said vehicle, having in-

duction and eduction openings, actuated by said motor, a longitudinally-extended, air-suction and vacuum-forming receiver upon the side of the vehicle and the surface of the ground, having a traveling support for the outer end thereof and a conductor connected therewith and a conductor connected with the said receiver and also connected with the induction-opening to the suction and blast apparatus, having swivel and socket joints, of 55 a crank-rod on the said vehicle, and a longitudinal rod connected with the outer end of said dust-receiver, and a hinged joint connecting said crank-rod with the rod on said receiver.

8. In a pneumatic dust-collector, a vehicle, suction and blast apparatus having induction and eduction openings, upon the platform of said vehicle, a motor actuating said suction and blast apparatus, a tube beneath the said platform, extending transversely thereto, and a conductor connected with said tube and the induction-opening to the suction and blast apparatus, elbows upon the ends of said tube and pivoted socket-joints connecting the said 70 elbows and said tube, air-suction and vacuum-forming receivers on each side of said vehicle and swivel-joints connecting the said elbows with said receivers, means for operating said receivers on the swivel-joints, and a receiver beneath the said platform, and a conductor connected rigidly with said receiver and said tube beneath the platform, and hinged brushes and aprons upon said receivers, and devices upon the platform of said 80 vehicle for operating the hinged brushes and aprons.

In testimony whereof I have signed my name to this specification in the presence of two subscribing witnesses.

JOHN T. HOPE.
